UNITED STATES PATENT OFFICE.

ALEXANDER SALOF, OF OAKLAND, CALIFORNIA.

FOLDING UMBRELLA.

1,065,729.

Specification of Letters Patent. Patented June 24, 1913.

Application filed August 14, 1912. Serial No. 714,984.

To all whom it may concern:

Be it known that I, ALEXANDER SALOF, a citizen of the United States, and a resident of Oakland, in the county of Alameda and State of California, have invented certain new and useful Improvements in Folding Umbrellas, of which the following is a specification.

My invention is an improvement in folding umbrellas, and has for its object, the provision of a simple, inexpensive, easily operated device of the character specified, wherein a frame is provided, consisting of a sectional stick, and means for holding the sections of the stick in rigid alinement, folding ribs having stretchers, and folding braces, together with a locking mechanism for the stretchers, operated by the braces, and a locking mechanism for the braces operated by the runner.

In the drawings: Figure 1 is a front view of the frame of the improved umbrella; Fig. 2 is an enlarged longitudinal section through the runner, with the parts in one position; Fig. 3 is a similar view, with the parts in another position; Fig. 4 is an enlarged longitudinal section, through the handle, with the parts in one position; Fig. 5 is a similar view, with the parts in another position; Fig. 6 is a longitudinal section of a portion of the stick; Fig. 7 is an enlarged front view of a portion of the runner, with the parts in one position; Fig. 8 is a similar view, with the parts in another position; Fig. 9 is a sectional view of a portion of a rib and brace, with the parts in opened position; Fig. 10 is a similar view with the parts folded; Fig. 11 is a perspective view of the hinge between the sections of the stick bracing mechanism; Fig. 12 is a section on the line 12—12 of Fig. 2; and, Fig. 13 is a section on the line 13—13 of Fig. 3.

The present embodiment of the invention comprises a folding frame, composed of a sectional stick, sectional ribs, and braces of a particular construction, connecting the ribs to a runner. The stick is composed of three tubular sections 1—2 and 3, the said sections being in alinement when the frame is unfolded and open.

The section 1 has connected to its lower end, a handle or grip 4 and the said grip is longitudinally recessed, as shown at 5, to receive the section 1. A plug or filling block 6 is secured in the end of the section, by means of a double headed rivet 7, and a

spring 8 is seated at its lower end on the plug or block.

A cylindrical block 9 is arranged above the spring, the said block having a transverse opening for receiving a transverse pin 10, whose ends extend beyond the block on both sides, and engage longitudinal slots 11 in the stick section. A wire or rod 12 is passed longitudinally through the block 9, and the spring 8 engages the lower end of the rod.

The upper end of the rod or wire is secured to a substantially conical expanding head or spreader 13. A sleeve 14 is arranged in the stick section above the spreader, and the lower end of the sleeve is shaped internally to fit the spreader, being tapering or conical, as shown at 15, and the sleeve is slotted longitudinally at the said end, as shown at 16.

It will be evident that when the head or spreader is forced into the lower end of the sleeve, the said end will be expanded, and will be clamped against the inner surface of the stick section, to hold the parts from longitudinal movement. The upper end of the sleeve is closed, and a wire or rod 17 is threaded into a longitudinal recess in the said end.

The upper end of rod 17 is threaded into the lower end of a cylindrical block 18, slideable in the stick section, and the upper end of the said block is slotted transversely to receive one end of a bar 19. A shell 20 having oppositely arranged longitudinal slots 90 21 is connected to the bar 19 at the lower end of the shell, the said lower end being transversely slotted to receive the adjacent end of the bar, and rivets 22 are passed through the ends of the bar and the block 95 and shell, to pivotally connect them to the bar. The shell 20 is connected rigidly to the stick section 2, by means of a rivet 21^a.

The above mentioned elements, namely, the block 9, rod 12, and head 13 are moved 100 toward the sleeve 14, by means of a collar 23, mounted to slide on stick section 1 above the grip, and the said collar is provided with overlying lugs 24 for engaging over the ends of pin 10, to lock the block 9 from longitudinal movement. The said lugs 24 are so arranged, that when the collar is turned angularly on the stick section in one direction the lugs engage over the ends of the pin, and when turned in the opposite direction they are disengaged.

The block 18 is in section 2 of the stick,

and the shell 20 is at the junction of the sections 1 and 2 when the stick is unfolded. The shell extends across the junction or joint of the sections, to hold them in alignment, and when it is desired to fold the sections 1 and 2, the spreader 13 is moved downward in a manner to be presently described, to release the sleeve 14. The sections 2 and 3 are then drawn away from the section 1, the sleeve 14 slipping out of the adjacent end of the section 1. The section 3 as it is drawn away from the section 2 will pull the block 18, the rod 17, and the sleeve 14 longitudinally of the section 2, until the bar 19 is opposite the joint. When this takes place, the section 3 may be folded on the section 2.

Each of the ribs or stretchers is composed of an inner section 25, and an outer section 26. The said sections are of the usual U or channel shape cross section, and the outer end of the inner section is received in one end of a U-shaped shoe or housing 27. The said outer end is pivoted to the housing by a rivet 28, and the inner end of the outer section is connected to the housing by means of a link 26^a (Fig. 10) in order that the section 26 may fold upon the section 25 as indicated in dotted lines in the said Fig. 10. The link when the sections are folded, stands at approximately a right angle to both sections, thus permitting them to fold smoothly upon each other.

The sides of the shoe or housing are extended downwardly, and one end of a bar 30 is pivoted between the extended sides, as shown at 31. The meeting ends of the rib sections are beveled in opposite directions, and the outer section is provided with a longitudinally extending lug 32, which engages beneath the end of the inner section.

Each of the sections 25 and 26 is provided with a filling block 33 and 33^a respectively at its meeting end, to make a rigid joint, and the filling block is secured in place in any desired manner, in the channel of the sections. The bar 30 is rounded at the end adjacent to the rib or stretcher, and the one end of the rounded portion bears against the lug 32, to hold it against the under face of the filling block of the inner section.

The inner end of the inner section is pivoted to the notch 34, on the section 3 of the stick, and each rib is connected intermediate its ends to the runner to be described, by means of a sectional brace 35-36 and 37. The sections 35 and 36 are in alignment, when the umbrella is unfolded, and the section 37 is pivoted to the section 35, near its outer end, as shown at 38.

The outer section 36 of the brace has a bar 40 secured in its inner end, and the inner end of the said bar extends inwardly beyond the pivotal connection 41 of the two sections 35 and 36. The free inner end of

bar 40 is slotted transversely, as shown at 42, to receive a finger or lug 43 on the sliding bar 39.

The sections 35 and 36 are tubular, as shown at 44, at their adjacent ends, to receive and hold the bars 39 and 40. The inner end of section 35 is pivoted to a notch 45 on the runner to be described, and the inner end of section 37 is pivoted to a notch 46 below notch 45, and also on the runner.

When the inner ends of the braces are moved on the stick toward each other, with sections 35 and 36 in alignment, the bar 39 is moved outwardly in the tubular portion of section 35, and the finger 43 is moved into the slot or recess 42, and the sections, 35 and 36, are locked in alignment with each other. When the notches 45 and 46 are moved away from each other, the finger or lug is withdrawn, and the sections 35 and 36 may be folded upon each other.

The runner before mentioned consists of a sleeve 47 fitting the stick, and having the notch 45 at its upper end, a second sleeve 48, fitting over sleeve 47 and having notch 46 at its upper end, and a third sleeve 49, fitting over both sleeves 47 and 48. The sleeve 48 is shorter than sleeve 47, and the lower end of sleeve 49 is reduced at its lower end, as shown at 49^a, to fit sleeve 48, below the lower end of sleeve 47.

Sleeve 47 is provided with a pair of annular ribs 50 and 51, intermediate its ends, and a coil spring 52 encircles the sleeve 47 between the lower end of sleeve 48 and rib 50. A second spring 53 encircles the sleeve 47 between ribs 50 and 51, and the rib 51, seats against the upper end of the reduced portion 49^a of sleeve 49. The sleeve 49 is slotted longitudinally, as shown at 55, and is provided with notches 56 and 57, at opposite ends and opposite sides of the slot.

The lower end of sleeve 48 is provided with oppositely arranged lugs 58 and 58^a, at its lower end, the former engaging slot 55, and the latter a short slot 59, opposite slot 55. The sleeve 48 is also provided with an annular rib 60, intermediate its ends, which forms a stop for engaging the upper end of sleeve 49.

The slot 59 has a notch 59^a, at the same side as notch 56, so that when the sleeves 47 and 49 are turned with respect to each other, the lugs 58 and 58^a may be engaged and disengaged with notches 56 and 59^a. The sleeve 48 may be moved downwardly on sleeve 47, to release the fingers 42 from the slots or recesses 43 to permit the brace sections 35 and 36 to be folded on each other. When the lugs 58 and 58^a are released from notches 56 and 59^a, spring 52 forces sleeve 48 to its original position.

The stick is provided with openings 61 for engagement by a latch 62, pivoted at 63 on the sleeve 47, to hold the runner in ele-

vated position, and a spring 64 is provided for holding the latch in engagement with the opening. The section 3 of the stick is provided with a tip 65, and the grip 4 may be of any desired shape.

When it is desired to fold the frame, the operation is as follows:—The collar 23 is designed to hold the ribs or stretchers in folded position, as shown in Fig. 5, and is also designed to separate the sections of the stick. For this function the collar is engaged with the pin 10, as shown in Fig. 5, the said collar being slideable on the stick in the usual manner. The collar is first moved into the dotted line position of Fig. 4, and is then turned to engage the lugs 24 above the ends of the pin. When the collar is now moved back toward the grip, the block 9 and the spreader 13 is moved with the collar, thus releasing the clamping action of the sleeve 14. The sections 2 and 3 are thus separated from the section 1, and by pulling the sections 3 and 2 away from each other, until the bar 19 is opposite the joint between them, the said sections 2 and 3 may be folded upon each other.

The spring 52 is designed to move the sleeve 48 upward, to hold the rib sections in alinement, while the spring 53 prevents movement of the sleeves 48 and 49 with respect to each other. It will be noted that the section 1 of the stick is provided with an annular shoulder 1^a near its upper end, and that the sleeve 14 is provided with an external annular shoulder 14^a for engaging beneath the shoulder 1^a when the sections are locked together.

To disengage the brace sections, the sleeve 48 is pressed downwardly, until the lugs 58—58^a are in register with notches 56 and 59^a. The sleeve 48 is then turned slightly to engage the lugs with the notches. This movement of the sleeve moves all of the bars 39 inwardly, and disengages each of the fingers 43 from the openings 42 of the outer section. When the braces are folded, the stretcher sections are disengaged, and may also be folded. It will be noticed that the alinement of the brace sections locks the stretcher sections in place. The notch 34 is riveted to the stick, as shown at 67. The elements 9, 12, 19 and 13 are preferably integral, although it is obvious that they may be separate if desired.

I claim:

1. In a folding umbrella, a rib composed of alined sections, links arranged on opposite sides of the adjacent ends of the sections and pivotally connected thereto, a housing connected with the outer end of the inner section, said sections having their inner ends beveled in opposite directions to permit the outer section to fold upwardly upon the inner section, the said ends contacting when the sections are in alinement,

said outer section having an inwardly extending lug engaging beneath the adjacent end of the inner section, a brace pivoted to the housing between the connection of the links with the respective sections and having a cam shaped head for engaging the lug and holding it against the inner section when the umbrella is unfolded.

2. In a folding umbrella, a folding rib comprising inner and outer alined sections, the adjacent ends of the sections being oppositely beveled on their upper faces, a pair of links connecting the sections, the said ends contacting when the sections are in alinement, the outer section having an inwardly extending lug engaging beneath the outer end of the inner section, and a brace pivoted to the outer end of the inner section between the connection of the links with the sections and having means for engaging the lug and pressing it against the inner section when the umbrella is unfolded.

3. In a folding umbrella, a plurality of braces, each comprising alined inner and outer sections, a pivotal connection between the meeting ends of the sections, the outer section having a longitudinal recess at its inner end, said sections being of channel shape, a bar slideable in the channel of the inner section toward and from the recess and having a finger for engaging the recess to lock the sections in alinement, a runner comprising an inner sleeve having a notch at its upper end, the inner section of the brace being connected to the notch, a second sleeve slideable on the first sleeve, and provided with a notch, a link connecting the bar having the finger to the notch, an inclosing sleeve on the lower ends of the first and second sleeves, said first sleeve having an annular rib below the lower end of the second sleeve, a spring between the rib and the second sleeve for pressing the notches together, and means in connection with the second sleeve and the inclosing sleeve for locking said second sleeve to the inclosing sleeve with the notches separated.

4. In a folding umbrella, a plurality of braces, each comprising alined inner and outer sections, a pivotal connection between the meeting ends of the sections, the outer section having a longitudinal recess at its inner end, said sections being of channel shape, a bar slideable in the channel of the inner section toward and from the recess and having a finger for engaging the recess to lock the sections in alinement, a runner having notches movable toward and from each other, the inner section being connected to the upper notch, a link connecting the bar having the finger to the other notch, a spring pressing the notches together, and means for separating the notches to release the finger from the recess.

5. In a folding umbrella, a plurality of

braces, each comprising alined inner and outer sections, a pivotal connection between the meeting ends of the sections, the outer section having a longitudinal recess at its inner end, said sections being of channel shape, a bar slidale in the channel of the inner section toward and from the recess and having a finger for engaging the recess to lock the sections in alinement, a runner 10 having a notch for connecting the inner ends of the inner sections together, a second notch movable on the runner toward and from the first notch, a connection between the said second notch and the sliding bars of all the 15 braces for simultaneously moving the said bars to engage and disengage them from the recesses, a spring pressing the second notch toward the first notch, and means for holding the said notch away from the first 20 notch.

6. In a folding umbrella, a plurality of braces, each comprising alined inner and outer sections, a pivotal connection between the meeting ends of the sections, the outer 25 section having a longitudinal recess at its inner end, said sections being of channel shape, a bar slidale in the channel of the inner section toward and from the recess

and having a finger for engaging the recess to lock the sections in alinement, a runner 3c having a notch for connecting the inner ends of the inner sections together, a second notch movable on the runner toward and from the first notch, and a connection between the said second notch and the sliding bars of all the braces for simultaneously 35 moving the said bars to engage and disengage them from the recesses.

7. In a folding umbrella, a plurality of braces, each comprising alined inner and outer sections, a pivotal connection between the meeting ends of the sections, the outer section having a longitudinal recess at its inner end, said sections being of channel shape, a bar slidale in the channel of the 45 inner section toward and from the recess and having a finger for engaging the recess to lock the sections in alinement, a link connected at one end to each bar, and a notch connected to the other ends of the links for 50 simultaneously moving the bars.
